DIRECTION SIGNAL LAMP FOR AUTOMOTIVE VEHICLES

Donald Lee Du Sell, Liverpool, N.Y., assignor to R. E. Dietz Company, Syracuse, N.Y., a corporation of New York

Filed Dec. 31, 1959, Ser. No. 58,881

Term of patent 14 years

(Cl. D48—32)

FIGURE 1 is a front elevation of a direction signal lamp embodying my new design, the rear elevation of the lamp being the same;

FIGURE 2 is a side elevation thereof, the opposite side being the same; and

FIGURE 3 is a horizontal sectional view thereof taken substantially along line 3—3 of FIGURE 1.

I claim:

The ornamental design for a direction signal lamp for automotive vehicles, substantially as shown.
